(57) **CLAIM**

The ornamental design for a hydration sleeve, as shown and described.

DESCRIPTION

FIG. 1 is a perspective view of a hydration sleeve showing our new design;

FIG. 2 is a front elevational view of the hydration sleeve of FIG. 1;

FIG. 3 is a rear elevational view of the hydration sleeve of FIG. 1;

FIG. 4 is a left side elevational view of the hydration sleeve of FIG. 1;

FIG. 5 is a right side elevational view of the hydration sleeve of FIG. 1;

FIG. 6 is a top plan view thereof; and,

FIG. 7 is a bottom plan view thereof.

The broken lines in the drawing depict environmental subject matter only and form no part of the claimed design.

1 Claim, 6 Drawing Sheets
